AUTOMOBILE DOOR LOCK OPERATING
MEANS

James Paris Jones, East St. Louis, Ill.

Application August 24, 1935, Serial No. 37,729

1 Claim. (Cl. 74—501)

This invention relates to door locks and more particularly to locks for the doors of an automobile.

In accordance with the present invention an improved lock for automobiles is provided together with positive and efficient means for remotely controlling the door locks to the end that the doors may be simultaneously unlocked, and also to the end that the locking and unlocking of the doors may be under the control of an occupant of the vehicle, preferably the operator thus promoting safety, and under such conditions obviously, children will not be enabled to unlock a door unknown to an adult occupant of the automobile.

The invention together with its objects and advantages will be best understood from a study of the following description taken in connection with the accompanying drawings wherein:

Figure 1 is a side elevational view of an automobile with parts broken away and illustrating the application of the invention.

Figure 2 is a detail side elevational view showing the manner of operatively connecting the locks for the individual doors with the brake lever.

Figure 3 is a view taken at right angles to Figure 2.

Figure 4 is an enlarged detail sectional view showing more clearly the structural features of a door lock embodying the features of the present invention.

Figures 5 and 6 are detail views taken substantially on the lines 5—5 and 6—6 of Figure 4.

Figure 7 is a perspective view of a lock bolt.

Figure 8 is a fragmentary detail sectional view showing the clamp means for connecting the control wires of the lock bolt with the brake lever.

Figure 9 is a perspective view of one of the members forming part of a two-part clamp used for connecting the operating or control wires with the brake lever.

Figure 10 is a perspective view of the clamp member complementary to the clamp member shown in Figure 9.

Figure 11 is a perspective view of a clamp member used in securing one end of the sheathing provided for the control wires.

Figure 12 is a perspective view of a clamp member complementary to the clamp member in Figure 11.

Referring to the drawings by reference numerals it will be seen that 5 indicates generally an automobile of a well-known type, the same being provided with four doors including a pair

of front doors 6 and a pair of rear doors 7. Adjacent the doors 6 and 7 there is provided a lock indicated generally in Figure 1 by the reference numeral 8.

A detailed description of one lock 8 will teach the structure of the other locks.

As best shown in Figure 4, each lock 8 comprises a tubular casing or barrel 9 that has a threaded end extending through an opening in the jamb 10 of a door and secured to the jamb 10 by lock nuts 11.

Having a sliding working fit in the barrel or casing 9 is a lock bolt 12 provided with a slot 13 through which extends a transversely disposed stop pin 14 that cooperates with the slot to limit movement of the lock bolt in either of two directions and to prevent rotative movement of the bolt.

The bolt 12 has a tapered end 12a that is receivable within a conical tapered socket 15 fitting within a suitable opening provided in a door of the automobile, and having at one end an integral disk or plate 16 through the medium of which and screws 17 the socket 15 is secured in position. For operating the bolts 12 of the locks 20 there are provided for the bolts operating wires 18 which are suitably secured at one end to the apertured and notched ends 19 of the respective bolts 12 and as best shown in Figures 4 and 7.

At the respective free ends the wires 18 are 30 clamped between a pair of complementary clamping members 20, 20a.

As best shown in Figures 8, 9 and 10 the complementary clamping members 20a, 20 are provided in their meeting faces with mating grooves 35 21 in which are clamped the wires 18 as shown in Figure 8. The clamping members 20, 20a are secured together through the medium of bolts or other fastening means 22.

One of the clamping members, for example the 40 clamping member 20a has formed integrally therewith a pin 23 which extends through a suitable opening 24 provided therefor in one end of a control lever 25. In the present instance the control lever 25 is the emergency brake lever of an automobile and is pivoted at one side of the transmission casing as at 26 and in a conventional manner. Securing the pin 23 journalized within the opening 24 is a pin 27 between which 45 and the adjacent side of the lever 26 is disposed a washer 28.

The bolts 12 are normally projected for locking the respective doors, through the medium of coil springs 28a suitably confined within the cas- 50

ing 8 and bearing against the bolt 12 in a manner clearly shown in Figure 4.

From the above it will be seen that upon manipulating the lever 25 as when, for example, the lever is swung in a clockwise direction (Figure 2) incidental to an application of the emergency brakes, a pull will be exerted on the cables or wires 18 for retracting the bolts 12 out of engagement with their respective sockets 15 thus 10 unlocking the doors 6 and 7 simultaneously and in a single operation. Obviously, therefore, upon manipulation of the lever 25 in a reverse direction to release the brakes, springs 28a will be free to act on the bolts 12 for projecting the latter 15 to engage the ends 12a of the bolts with the sockets 15 for simultaneously locking all the doors 6, 7 of the automobile.

The cables 18 are provided with suitable flexible sheathings 29. At one end the sheathings 20 29 are anchored through the medium of a clamp consisting of a pair of complementary clamp members 30, 30a, best shown in Figures 11 and 12. In their meeting or confronting faces the clamp members 30, 30a are provided with grooves 31 25 which receive one end of the sheathings 29 as best shown in Figure 3. These clamp members 30, 30a are secured together through the medium 30 of bolts or other suitable fastening means 32, and clamping member 30 has an angular end secured to the transmission casing as at 30'.

Each flexible sheathing 29 is also provided at one end with a cap 33 through the medium of which the sheathing is connected with the casing 35 8, cap 33 being threaded on one end of the casing 8 as shown in Figure 4.

From the above it will be seen that I have provided a lock for the doors of automobiles whereby the doors can be simultaneously locked or unlocked, and whereby unauthorized unlocking of the doors, especially by child occupants of the 5 automobile can positively be guarded against.

It will be understood that while the door locks are preferably disclosed as being controlled by the emergency brake lever, the cables may be suitably connected to the brake rods for carrying 10 out the function and object of the invention. It will be further understood that other changes may be made, such as for example, a relocation of the locks 8 without departing from the principles of the invention and the scope of the 15 appended claim.

Having thus described the invention, what is claimed as new is:

In combination, a brake lever, a support for the brake lever, a clamp block rockably connected 20 to the lower portion of the said lever, said block being divided into a pair of sections, a bracket secured to the said support, a clamp plate secured to the bracket, a plurality of elongated flexible conduits having one end clamped between 25 the clamp plate and the bracket, control wires extending through the conduits and engaged between the sections of the said clamp block, and means for holding the sections of the block in 30 clamping relation with the said wires, one of said sections of the clamp block being provided with a trunnion disposed through an opening in the brake lever, and means on the trunnion preventing return of the trunnion through the said 35 opening.

JAMES PARIS JONES.
